UNITED STATES PATENT OFFICE.

CHARLES HILBERT, OF SING SING, NEW YORK, ASSIGNOR TO HIMSELF,
JOHN J. MAHANEY, AND JOSEPH STERN, ALL OF SAME PLACE.

INHALER.

SPECIFICATION forming part of Letters Patent No. 276,968, dated May 1, 1883.

Application filed December 1, 1882. (No model.)

To all whom it may concern:

Be it known that I, CHARLES HILBERT, a citizen of the United States, residing at Sing Sing, in the county of Westchester and State 5 of New York, have invented certain new and useful Improvements in Inhalers, of which the following is a full, clear, and exact description.

This invention relates to the vaporization of ether for the purpose of administering the same as an anæsthetic; and my invention consists, essentially, in surrounding the body of a vessel for containing the anæsthetic with a jacket adapted to receive and hold a quantity of heated water, whereby the said vessel is 15 warmed to a degree sufficient to raise its contents to about the temperature of the human body, thereby effecting the vaporization of the anæsthetic very readily and obtaining a free flow of such vapor, while at the same time 20 the danger attending its administration in a cold state is avoided.

The drawing represents in sideelevation, the jacket being in section, an apparatus embodying my invention.

25 The letter A designates a cylindrical shell, provided with end caps, B B', at its upper and lower ends, respectively. The cap B is interiorly screw-threaded to engage a screw-thread on the exterior of the upper end of the shell A, and the cap B' overlaps the lower end of the shell A, and is soldered or sweated thereto. The interior of the shell A is adapted to contain a cake of magnesia or other pulv 30 erulent material, or such material in a powdered state as may be desired, for the purpose of absorbing the anæsthetic. The cap B is provided with an opening, into which a neck, b, is screwed. This neck b has a channel-way leading into the opening in the cap B, and is connected to an inhaler or face-mask, M, by means of a tube, t. The cap B' is also provided with an opening, into which a neck, b', is screwed. The neck b' has a channel-way leading into the opening in the cap B', and adapted to be opened or closed by means of a plug, P. A bulb or other air-forcing device, a, is connected to the neck b' by means of a tube, t'.

It is intended when the apparatus is not in use to remove the neck b and substitute there-

for a stopper or a neck provided with a plug, so as to close the vessel at both ends and prevent evaporation.

J designates my improved hot-water jacket, consisting of a cylindrical shell closed at 55 both ends, surrounding and soldered or sweat-ed to the shell A, the exterior of the shell A forming part of the jacket J. An opening, I, is formed in the jacket J, provided with a cup-shaped neck, e, through which hot water may 60 be introduced into the jacket, and adapted to be tightly closed by means of a stopper, s. It will be seen that the water in the jacket J comes in direct contact with the exterior of the shell A, and the shell A is thereby heated, 65 so as to raise the temperature of the absorbed anæsthetic to the desired extent.

Two handles, h h', are shown attached to the jacket J, which may be employed to suspend the apparatus, by means of a strap or cord, 70 from the shoulder of the operator, thus leaving both hands free.

The operation is as follows: Referring par-ticularly to the apparatus shown in the draw-ing, the absorbent material contained in the 75 receiver thereof is first saturated with the de-sired anæsthetic, and the plug P is turned to open the channel-way in the neck b'. After the anæsthetic has been absorbed by the packing the water-jacket J is filled with hot water, there-80 by heating the receiver containing the anæs-thetic and vaporizing the anæsthetic, which va-por escapes through the tube t into the face-mask M. To increase the flow, air is forced 85 into the apparatus, as by bulb a. A gradual pressure on the air-forcing apparatus will in-sure a steady flow of the vaporized anæsthetic of sufficient strength to produce anæsthesia very quickly, and the flow may be regulated by increasing or diminishing the pressure on 90 the air-pump.

When applied to inhalers wherein the anæsthetic is drawn from the receiver by inhalation, my water-jacket will be found of large practi-cal value, as by it the anæsthetic in the receiver 95 can be vaporized, and will flow steadily, in the form of a dry gas, to the point of application. The vaporization of ether, for instance, is in-creased to such extent by heat that in the ap-paratus shown in the drawing and hereinbefore 100

described the flow of vaporized ether, after the hot water is introduced into the water-jacket, is so great that anæsthesia can be produced without forcing air into the receiver; but when air-pressure is not employed it is advisable to hold the apparatus above the patient.

What I claim as my invention, and desire to secure by Letters Patent, is—

An apparatus for administering anæsthetics, substantially such as described, having a re-

ceiver for the anæsthetizing material provided with a jacket surrounding the said receiver, and adapted to contain heated water to vaporize the anæsthetic in the receiver, as set forth.

In testimony whereof I have hereunto set my hand this 6th day of October, A. D. 1882.

CHARLES HILBERT.
